(57) **CLAIM**

The ornamental design for a pet feeding device, as shown and described.

DESCRIPTION

FIG. 1 is a perspective view of a pet feeding device showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is perspective view showing an opened drawer of the pet feeding device;

FIG. 9 is an exploded view showing a transparent cover being taken away from a body of the pet feeding device;

FIG. 10 is another exploded view showing the transparent cover and a transparent rolling ball being taken away from the body respectively;

FIG. 11 is an enlarged view of the transparent cover in FIG. 10; and,

FIG. 12 is an enlarged view of the transparent rolling ball in FIG. 10.

The broken lines depict unclaimed features of the pet feeding device that form no part of the design claim but are shown for purposes of illustration.

1 Claim, 12 Drawing Sheets
